UNITED STATES PATENT OFFICE

HERBERT BEE, OF MANCHESTER, NEW HAMPSHIRE, ASSIGNOR TO WOODBURY SHOE MFG. CO., OF DERRY, NEW HAMPSHIRE, A CORPORATION OF NEW HAMPSHIRE

BOOT OR SHOE AND SHANK STIFFENER THEREFOR

Application filed June 6, 1929. Serial No. 368,797.

My present invention relates to boots and shoes, and more particularly to boots or shoes having incorporated therein a metallic arch supporter, and includes also the novel arch 5 supporter or shank stiffener per se.

An important object of the present invention is the provision of a boot or shoe which will have incorporated therein a longitudinal arch supporter.

10 Another object of the invention resides in the provision of an automatically locked arch, in said shoe, due entirely to the novel structure of the arch supporter or shank stiffener utilized in said shoe.

15 An important result of this locked arch is that the supporter, when the weight of the wearer is placed thereon, will be brought toward the foot, instead of bending back or away from the foot thus assuring a constant 20 arch supporting function. This feature is extremely important, as when the supporter is allowed to yield or bend back, it does not permit or provide full arch supporting capacity.

25 Another object of the invention resides in the particular construction of arch supporter utilized. The body of this arch supporter is of the well known cottage shank type, with the important exception of the forward end 30 thereof which is under the ball of the foot. This forward end of the supporter is spooned, longitudinally but not laterally, the extreme forward end of said spoon being beveled on its under surface, in such manner as to leave

35 a sharp, square upper edge. Due to the spoon shape of the ball end of the supporter, this sharp edge will be in constant engagement with the under surface of the insole. When the weight of the wearer or the pressure of 40 the foot, is placed on the shoe, this sharp edge will "bite" into the said under surface of the insole, automatically locking the arch supporter in position, the rearward end of said supporter being provided with prongs or other suitable holding means, which are driven into the insole at the heel portion.

45 The benefits and advantages of this sharp spoon end will be instantly apparent to those skilled in the art, and since I believe that said shank stiffener, as well as the shoe in

which same is incorporated, are novel, I have claimed the same in the present application.

The above and other objects of the invention details of construction, and advantages, will be hereinafter more fully pointed out, 55 described and claimed.

Referring to the drawings, illustrating a preferred embodiment of the invention,

Fig. 1 is a side elevation of a lady's pump, partially in section, with my novel arch sup- 60 porter in position;

Fig. 2 is a vertical sectional elevation on the line 2—2 of Fig. 1;

Fig. 3 is a fragmentary longitudinal sec- 65 tional view, on an enlarged scale, illustrating the forward end of the shank stiffener, and its position in the shoe relative to the insole and outsole;

Fig. 4 is a top plan view of the arch sup- 70 porter; and

Fig. 5 is a side elevation of said arch sup- 75 porter.

Referring now to the drawings for a par- 80 ticular description of the invention, its construction and assembly, 1 designates the up- 75 per materials of a shoe, assembled on an in- sole 2 in usual manner.

Before the outsole is affixed, my novel arch supporter 3 is applied to the shoe, the rearward end of this arch supporter having a 85 pair of pointed prongs 4, which are driven into the insole at the heel portion thereof, this being the only operation necessary to attach this arch supporter to the shoe. The shoe 90 illustrated in the present application is of the well-known McKay type, and subsequent to the arch supporter attaching operation, the outsole 5 is laid, temporarily secured to the insole, and then permanently attached thereto by through and through stitching, 95 whereupon the heel 6 is attached. The outsole may be temporarily attached at the forward end before installation or incorporation of the arch supporter, if desired.

The shank stiffener illustrated has a curved body portion 7 constructed similar to the well known cottage shank supporter, the forward end 8 of this supporter being spooned or curved in a direction reverse to the curve of the body 7, so that the general longitudinal 100

contour of the supporter is that of a reverse curve. The extreme forward end of the supporter is squared, the under surface of this forward end being chamfered or beveled as 5 illustrated at 9, leaving a sharp forward upper edge 10. When positioned in the shoe, between the insole 2 and outsole 5, as clearly illustrated in Fig. 3, the spoon end 8 brings the sharp edge 10 into contact with the under 10 surface of the insole 2 at the ball of the foot. Thus when the weight of the wearer is placed in a shoe, this will cause said edge 10 to bite into the under surface of the insole, locking the supporter in position between the prongs 15 4 and the point at which the edge 10 of the supporter has bitten into the insole.

The biting of the edge 10 into the insole 2 will never be sufficient to penetrate through the insole, and thus cannot possibly injure 20 the foot of the wearer. In prior shoes of this type, wherein the forward end of the shank stiffener was loose, and free to slide on action of the foot during walking, the shank stiffener would bend back away from the arch of the foot, and would thus not have a constant arch supporting capacity. In 25 shoes where the forward end of the arch supporter has been fixed in position, the expense of manufacturing such shoes has been increased due to the additional operation or 30 operations necessary to attach said forward end, and the attaching instrumentalities have frequently penetrated the insole, resulting in 35 injury to the wearer, damage to stockings, and other disadvantages.

By my present invention, eliminating separate attaching elements for the forward end of the arch supporter I am enabled to more 40 cheaply produce a shoe having a metallic arch 45 supporter incorporated therein, while at the same time assuring the wearer of an automatically or self-locked arch, and constant 50 arch support.

While I have necessarily described my 55 present invention somewhat in detail, it will be appreciated that the showing of a McKay 60 shoe is for illustrative purposes only, and that I may vary the size, shape, style, type and 65 arrangement of parts within reasonably wide 70 limits without departing from the spirit of 75 the invention.

My invention is further described and 80 defined in the form of claims as follows:

1. In a boot or shoe, an insole, an outsole, 85 a metallic arch supporter positioned between 90 said insole and outsole, said supporter being 95 fixed to said shoe at its rear end only, the 100 forward end of said supporter being upwardly 105 curved, and having its extreme forward 110 end beveled on the under side, thus forming 115 a sharp edge on the forward end of the 120 supporter, whereby, on pressure of the foot being 125 applied to said shoe, said sharp edge will bite 130 into the under surface of the insole, and automatically lock the supporter in position.

2. A metallic arch supporter of the kind described, comprising a curved body portion, and a forward end curved in a direction reverse to the curve of the body portion, the said curved end of said forward portion 70 being beveled on its under surface to provide a sharp upper edge on said forward portion.

In testimony whereof, I have signed my name to this specification.

HERBERT BEE.
